UNITED STATES PATENT OFFICE.

PAUL L. ROEDIGER, OF PLEASANTVILLE, NEW JERSEY.

JAR AND BOTTLE CLOSURE.

No. 890,302.

Specification of Letters Patent.

Patented June 9, 1908.

Application filed November 6, 1907. Serial No. 400,923.

To all whom it may concern:

Be it known that I, PAUL L. ROEDIGER, a citizen of the United States, residing at Pleasantville, in the county of Atlantic, State of New Jersey, have invented a new and useful Jar and Bottle Closure, of which the following is a specification.

My invention consists of a closure for a vessel of the order of a jar or bottle, comprising a cap, which is provided with lips of angular or deflected form, which provides strength and elasticity to the same in their engagement with members on the vessel, as will be hereinafter described.

For the purpose of illustrating my invention, I show in the accompanying drawing an embodiment of the same as producing satisfactory results, but the important instrumentalities thereof may be variously disposed, and so it is to be understood that the invention is not limited to the specific arrangement and organization of said instrumentalities.

Figure 1 represents a perspective view of a cap member of a closure for a vessel embodying my invention. Fig 2 represents a side elevation of a vessel to which said cap is applicable. Fig. 3 represents a side elevation of the cap partly broken-away and of the adjacent portion with which the same engages. Similar letters of reference indicate corresponding parts in the figures.

Referring to the drawings:—A designates the neck of a jar, on whose exterior, about the mouth thereof, are the flanges B, with intervening vertical throats C, the lower edges of said flanges being inclined or spiral as at D.

E designates the closure of the jar, the same consisting of a cap formed of a top F, a side-rim G, and the lips H, the latter being inturned from both the side and bottom edge of said rim and so disposed as to be capable of passing downwardly through the throats C, and when the cap is rotated to engage the edges D of the flanges B, as will be hereinafter again referred to. The rim G is continuous so as to completely encircle the neck of the jar and thus form a tight joint at the mouth thereof.

The lips H are deflected upwardly in V- or U-shape, whereby they are, in a measure, crimped or corrugated, producing limbs J whose angles or crowns K are adapted to contact with the edges D of the flanges, so that as the cap is rotated, said crowns solely

contact with and ride down said edges at right angles thereto and draw the cap firmly against the top of the jar and seat it thereon, thus hermetically closing and sealing the same. The limbs J are pieces continuous from the lower edge of the side rim turned inwardly and crimped upwardly, the resultant crowns thus having long bearing surfaces on the spiral edges of the flanges which will prevent slipping outwardly from said edges. Furthermore, the crimped portions of said limbs extend continuously inwardly from the lower edge of the rim, and so vastly increase the strength of the lips from end to end.

Especial attention is directed to the construction of the lips H, which, owing to their crimped or corrugated nature, possess increased strength, whereby they are not liable to be fractured or broken-off, while the cap is subjected to the tightening operation or held firmly in position, and the limbs of the lips add resiliency to the same, so that while the pressure of the cap on the jar is not dead and injurious in its nature, the cap is tightly held on its seat.

The crimps or corrugations of the lips H extend into the side rim G so as to crimp or corrugate the latter at the places of connection of said lips with said rim, thus vastly strengthening said places while the lips retain their resiliency.

The side-rim of the cap is scalloped or corrugated as at L, thus vastly strengthening the same and affording means which are convenient and easy to the fingers in rotating the cap in applying and removing the same, while also rendering said rim resilient in lateral direction, so as to yield to any inaccuracies in the sides of the flanges B.

The edges D are formed with scallops or notches M, into either of which the crowns of the lips may spring, so that said lips may take firmer hold of the flanges and be prevented from improper reverse rotation, said hold, however, being overcome when superior force is imparted to the cap to properly rotate it.

Having thus described my invention, what I claim as new and desire to secure by Letters Patent, is:—

1. A cap having a top, a continuous side rim, and securing lips, the latter being continuous from the lower edge of said rim and turned inwardly and having upwardly crimped portions forming crowns having ex-

tended bearing surfaces to engage locking flanges on a jar or like receptacle, said crimped portions extending continuously from said lower edge of the rim.

5 2. A cap formed of a top, a continuous corrugated side rim and securing lips, the latter being integral with and continued from the lower edge of said rim and extended inwardly and having upwardly crimped portions form-

ing extended-inwardly projecting bearing ¹⁰ surfaces for engagement with co-operating locking flanges on a jar or like receptacle said crimped portions extending continuously from the lower edge of the rim.

PAUL L. ROEDIGER.
